ATTORNEY.

UNITED STATES PATENT OFFICE.

CHARLES H. SPOTZ AND GEORGE A. SPENCER, OF PHILADELPHIA, PENNSYLVANIA.

BACK AND HEAD REST.

No. 884,534.

Specification of Letters Patent.

Patented April 14, 1908.

Application filed February 12, 1907. Serial No. 356,942.

To all whom it may concern:

Be it known that we, CHARLES H. SPOTZ and GEORGE A. SPENCER, of the city and county of Philadelphia, State of Pennsylvania, have invented an Improvement in Back and Head Rests, of which the following is a specification.

Our invention has reference to back and head rests and consists of certain improvements which are fully set forth in the following specification and shown in the accompanying drawings which form a part thereof.

The object of our invention is to provide a convenient portable device at small cost which may be adapted for use at sea shore, parks or even in the house for supporting the shoulders and head when occupying a reclining or sitting position.

Our object is further to make the back and head rest collapsible and also adjustable as more fully pointed out hereinafter.

Our invention consists of a portable frame comprising two main posts connected by a back and head support preferably of textile material, two struts for said end posts adjustably connected to the same, and a transverse bar for holding the upper portions of the posts and struts at a fixed distance apart.

Our invention also consists of the general construction above specified combined with means for supporting a parasol or umbrella above the head of the reclining occupant.

Our invention also comprehends details of construction which, together with the features above specified, will be better understood by reference to the drawings, in which.

Figure 1 is a sectional side elevation of our improved back and head rest; Fig. 2 is a rear elevation of the same; Fig. 3 is a plan view of the connecting parts at one corner; and Fig. 4 is a side elevation of the clamp support for the parasol or umbrella.

A A are the two main posts and are connected together by the canvas or other suitable web J to directly receive the back and head. The upper ends of these posts are provided with metal caps comprising the parts E E' hinged or hooked together at e and clamped in position upon the upper ends of the wooden posts by the bolts F. The flanges through which the bolts pass are so shaped that a slot or socket f is provided. Hinged to the bolts F and confined by the slots f are extensions of the sockets G G which are secured upon the upper ends of the struts C C. The sides of the sockets G G are

preferably provided with lateral flanges forming slotted sockets H having pins h. Hinged to the pin h in one of the slotted sockets H is the end of a socket I which is secured to a transverse tie bar D, the other or free end of which has a socket I' having a hook i to engage the other slotted socket H and its pin h as shown in Fig. 2.

The lower ends of the posts A and struts C may be thrust into the sand with the inclination of the canvas J at that desired, and the upper ends of the opposite posts and struts are held apart by the tie bar D. While this tie bar is more nearly associated with the struts C C, it is nevertheless, so near the posts and being connected by iron fittings thereto, that it may be considered as extending between them. It is evident that the particular location of this bar D is not essential so long as it holds the upper ends of the posts A A apart. It is perhaps preferable to arrange it to the rear of the plane of the posts and canvas so as not to come in the way of the hat of the occupant.

When the device is employed in the park or where the ground is hard, it is preferable to have the lower ends of the posts and struts provided with caps K and L respectively, having points which may engage the ground to prevent slipping of the ends of the said posts and struts.

When it is desired to collapse the apparatus, it is only necessary to unhook the part i from the pin h, fold the bar D down against the strut to which it is hinged, close the struts to the posts, and bring both posts together, wrapping the canvas about the series of posts, struts and bar.

As it is desirable to provide means for supporting a canopy over the occupant's head, we provide a clamp M for the tie bar D comprising two hinged parts which clamp over the bar under the influence of the clamping screw m. This clamp is provided with the socket M' and hook M² for supporting an umbrella or parasol. The clamp may be adjusted laterally along the length of the bar D or radially about it to bring the canopy in the proper position desired. Any other suitable form of canopy clamp or holder may be employed in lieu of that shown.

In practice we prefer to make the posts, struts and tie bar of wood because of lightness but it is evident that they may be made of metal if so desired.

While we prefer the construction shown as

having been found excellent as an embodiment of our invention for commercial use, we do not however restrict ourselves to the minor details of the construction as these 5 may be modified without departing from the spirit of our invention.

Having now described our invention, what we claim as new and desire to secure by Letters Patent, is:

- 10 1. A back and head rest consisting of two posts connected by a flexible support for the back and head of the occupant and freely adjustable to and from each other, combined with struts for holding the posts in upright 15 position, and a transverse tie bar having its ends connected with the tops of the posts by universal joints.
- 20 2. In a head rest, a metallic connection for the several hinged parts consisting of a socket post cap combined with a metallic socket piece G hinged to the post cap on an axis at right angles to the socket of the post cap, and a second socket part I hinged to the socket piece G on an axis at substantially 25 right angles to the hinge of the said socket piece G and post cap.
- 30 3. A back and head rest consisting of two posts connected by a flexible support for the back and head of the occupant, and freely adjustable to and from each other combined with struts for holding the posts in upright 35 position respectively hinged at their ends to the tops of the posts, a transverse tie bar for holding the upper ends of the struts at a fixed distance apart, connecting parts for adjustably uniting the posts, struts and tie bar consisting of a metallic part secured to the top of each post, a socket part secured to the top of each strut and hinged to the metallic 40 part on the top of the post, and metallic parts connected to the ends of the tie bar and

having a jointed connection with the metallic parts on top of the struts to enable it to fold down parallel to the struts.

4. In a back and head rest, the combination of the posts A A, flexible band J connecting them, metal heads B B for the tops of the posts consisting of parts E E' hinged together and clamped on the posts by bolts F F, socket pieces G G hinged upon the bolts F F, struts C C secured to the socket pieces G G, and a tie bar for holding the posts apart.

5. In a back and head rest, the combination of the posts A A, flexible bands J connecting them, metal heads B B for the tops 55 of the posts consisting of parts E E' hinged together and clamped on the posts by bolts F F, socket pieces G G hinged upon the bolts F F, struts C C secured to the socket pieces G G, and a tie bar for holding the posts apart 60 detachably jointed to the socket pieces G G.

6. A back and head rest consisting of two independent sets of rods jointed together at the top and adapted to be spread at their free ends to make contact with the ground 65 over a considerable area and said sets of rods being adjustable toward or from each other, combined with a textile band extending between two of said rods one of each set, and a spacing rod hinged to the other rods of the 70 two sets of rods near their upper parts for holding them at a distance apart, whereby the spacing rod is hinged to one rod of each set by a single hinge and to the other rod of each set by a double or universal hinge.

In testimony of which invention, we have hereunto set our hands

CHARLES H. SPOTZ.
GEORGE A. SPENCER.
